FIG. 2.

Inventor

John Teasay Collier

by Connally Bros
Atlys

UNITED STATES PATENT OFFICE.

JOHN VEASY COLLIER, OF NORTHAMPTON, ENGLAND, ASSIGNOR OF ONE-HALF TO THE NORTHAMPTON MACHINERY CO. LIMITED, OF NORTHAMPTON, ENGLAND, A CORPORATION OF GREAT BRITAIN.

MACHINE FOR REENFORCING INSOLES.

Application filed July 16, 1924. Serial No. 726,346.

To all whom it may concern:

Be it known that I, JOHN VEASY COLLIER, a subject of the King of Great Britain, residing at Northampton, in the county of Northampton, England, have invented certain new and useful Improvements in or Relating to Machines for Reenforcing Insoles, of which the following is a specification, reference being had therein to the accompanying drawing.

This invention relates to machines for reenforcing insoles by the application of a strip of canvas or other suitable material to the upturned lip thereof and comprises an improvement upon the machine described in our prior British specification No. 20801 of 1912.

The improvement constituting the present invention concerns the gripping presser members which press the reenforcing strip upon the sides of the upturned lip and upon the flat face of the insole adjacent said lip. The object of the invention is to obtain a greater downward pressure of the members, to more effectively force the covering strip into the corner formed by the lip and insole and to enable an insole to be reenforced by the above mentioned method in cases where the upstanding lip instead of standing up-right at right-angles is inclined relatively to the adjacent face of the insole.

It will be understood that when the upstanding lip is inclined the angle on one side thereof is less than a right angle. It is an important feature of the present improvement that the gripper presser members are arranged to operate in such a manner as to effectively press the reenforcing strip into the angular corner.

According to the invention the gripping presser members which as in the previous machine are carried upon a rocker frame actuated to impart the feed to the work and strip, and mounted and actuated independently of each other. The member which acts upon the outside of the lip operates downward while the member which acts upon the inside of the lip operates first with a lateral movement outwards and then with a downward movement.

The double movement of the last mentioned member results in the reenforcing strip being pressed against the inside of the

lip and also into the corner and upon the adjacent face of the insole. 55

The gripping presser members are actuated by suitable intermediate means from driven eccentrics or cams, and means are provided to enable the pressure imparted by said members to be regulated according to 60 requirements.

In order that the invention may be more clearly understood reference will be hereinafter made to the accompanying drawing 65 wherein:—

Figure 1 is a side elevation, partly in section, and

Figure 2 is a front elevation of a convenient embodiment of the invention.

In the illustrated embodiment of the invention the gripping presser member 1 for acting upon the outside of the lip *a* of the insole *b* is slidably mounted in or on the rocker frame 2 which latter swings on a pin or bolt 3 secured in the upper part of the machine frame 4. The presser member 1 is controlled and normally held raised by a compression spring 5 located between an angle piece 6, fixed on the rocker frame 2, so that the upper end of the presser member 1 passes therethrough and a washer 7 on said upper end. By means of a rod or link 8 operated by an eccentric 9 or equivalent the presser member 1 is moved downwards for pressing the reenforcing strip *c* upon the outside of the lip *a* and face of the insole *b*. For this purpose the eccentric rod or link 8 is connected to a sleeve 10 mounted on the presser member 1 and adapted to abut against shoulders 11 formed by a square 85 part of said member, which slides in the rocker frame 2 and prevents rotation of the presser member. The eccentric 9 or equivalent is formed or keyed on a driving shaft 12 from which the rocker frame 2 receives its motion in the manner set forth in the specification hereinbefore referred to. Said eccentric or equivalent moves the presser member 1 to a definite position and in order to enable the active pressure of the member upon the work to be varied the table or block 13 upon which the insole rests is made adjustable relatively to the member in a suitable manner. Conveniently the table or block 13 is located in a recess 14 in the rocker frame and has a screw threaded extension 90

95

100

105

which is received in a tapped hole 15 in said frame so that by screwing the extension into or out of the hole the position of the table or block may be varied as required. The table 5 or block projects from the rocker frame 2 through an opening 16 in the bed 17 of the machine and remains rigid in said frame during the operation of the machine.

The other gripping presser member 18 10 which acts upon the inside of the lip *a* is slidably mounted and spring controlled in a head 19 pivotally attached to the rocker frame 2 by means of a pin 20 or equivalent. Conveniently the presser member 18 is 15 formed like a plunger at its upper end to slide through a bearing on the head 19 which bearing also houses a compression spring 21 tending to hold the presser member raised for which purpose the spring 20 engages a collar 22 secured on the upper end of said member by a pin 23. This pin engages with recesses or notches 24 in the head 19 so as to prevent rotation of the presser member. Also pivotally mounted 25 on the rocker frame 2, (preferably on the pivot pin 20) is a rock lever 25 fitted at one end with an adjustable screw 26 to bear upon the upper end of the presser member 18, said screw being locked after adjustment by a nut device 27. At the other end 30 the rock lever 25 has suitable intermediate connections for operation from an eccentric 28 or equivalent on the aforesaid shaft 12, such connections conveniently comprising 35 an eccentric rod or link 29 and an eye piece 30 or equivalent. The rear portion of the head 19 is preferably bifurcated to embrace the rock lever 25, and both of these parts are situated in a slot or opening 31 in the 40 rocker frame 2.

There is provided between the rock lever 25 and the pivoted head 19 a suitable lost motion connection, such as may be formed by a pin 32 in the head and a slot 33 in 45 the lever, by which the latter moves the head upwards and which permits the rock lever to move downwards independently of the head for a purpose hereinafter set forth. In the normal position the presser member 50 18 is held with its lower operative end raised clear of the insole *b*. The first operation of the eccentric 28 or equivalent is to move the rock lever 25 and head 19 so that these parts turn as one on the pivot 20 and cause 55 the presser member to swing towards the lip *a* to press the strips *c* against the side thereof. The downward movement of the head 19 is now arrested by the contact of a foot 34 thereon with the lower end of the 60 aforesaid slot or opening 31 in the rocker frame. Further movement imparted to the rock lever by the eccentric 28 or equivalent causes the screw 26 in said lever to act upon the upper end of the presser member 65 and thereby move the latter downwards in

the member upon the reenforcing strips and flat face of the insole. This downward motion of the presser member takes place against the action of the controlling spring 21.

Upon reverse action of the parts by the eccentric 28 or equivalent, the rock lever 25 allows the presser member 18 to rise in the head 19 and then raises the latter to carry the presser member to normal position.

The gripping presser members 1 and 18 are suitably shaped at their lower ends for acting upon the respective sides of the lip *a* and adjacent insole faces.

The details of construction may be varied without departing from the scope of the invention.

What I claim then is:—

1. In an insole reenforcing machine, in combination a rocker frame for imparting feed to the work and reenforcing strip, a gripping presser member movable downwards on said rocker frame for acting upon the outside of the lip of the insole, a gripping presser member movable laterally and downwards on the rocker frame for acting upon the inside of the lip of the insole, and mechanism for actuating said presser members.

2. In an insole reenforcing machine, in combination, a rocker frame for imparting feed to the work and reenforcing strip, a gripping presser member movable downwards on said rocker frame for acting upon the outside of the lip of the insole, an eccentric and intermediate connections for actuating said presser member, a gripping presser member movable laterally and downwards on the rocker frame for acting upon the inside of the lip of the insole, and an eccentric and intermediate connections for actuating said presser member.

3. In an insole reenforcing machine, in combination, a rocker frame for imparting feed to the work and reenforcing strip, a spring controlled gripping presser member slidably in said rocker frame, an eccentric for moving said presser member downwards to act upon the outside of the lip of the insole, a head movable on the rocker frame, a spring controlled gripping presser member slidably in said head, a rock lever fulcrummed on the rocker frame and provided with an adjustable screw adapted to engage the presser member in the movable head, a connection between said head and the rock lever which permits the latter to move independently of the head, a stop for limiting the movement of the head and an eccentric for imparting movement to the rock lever and the head so as to cause the presser member in the latter to move laterally and downwards to act upon the inside of the lip of the insole.

4. In an insole reenforcing machine, in combination, a rocker frame for imparting feed to the work and reenforcing strip, a spring controlled gripping presser member 60
 5 slidable in said rocker frame, an eccentric acting through a link for moving said member downwards to act upon the outside of the lip of the insole, a head movable pivotally on the rocker frame, a spring controlled 65
 10 gripping presser member slidable in said head, a rock lever fulcrummed on the rocker frame and provided with an adjustable screw adapted to engage the presser member in the movable head, a pin and slot connection 70
 15 between the head and the rock lever whereby movement of the latter independently of the head is permitted, a foot on said head adapted to contact with the lower end of a slot in the rocker frame to limit 75
 20 the movement of the head, and an eccentric acting through a link for imparting movement to the rock lever and the head so as to cause the presser member in the latter to move laterally and downwards to act 80
 25 upon the inside of the lip of the insole.
5. In an insole reenforcing machine, in combination, a rocker frame for imparting feed to the work and reenforcing strip, a gripping presser member movable downwards 85
 30 on said rocker frame for acting upon the outside of the lip of the insole, a gripping presser member movable laterally and downwardly on the rocker frame for acting upon the inside of the lip of the insole, 90
 35 mechanism for actuating said presser members, and means for enabling the active pressure imparted by the presser members to be varied.
6. In an insole reenforcing machine, in combination, a rocker frame for imparting feed to the work and reinforcing strip, a gripping presser member movable downwards on the rocker frame for acting upon the outside of the lip of the insole, an eccentric and intermediate connections for actuating said presser member, a gripping presser member movable laterally and downwards on the rocker frame for acting upon the inside of the lip of the insole, an eccentric and intermediate connections for actuating said presser member and a table 100
 40 on which the insole rests said table being adjustable relatively to the presser members so as to enable the active pressure imparted by said presser members to be varied.
7. In an insole reenforcing machine, in combination, a rocker frame for imparting feed to the work and reenforcing strip, a spring controlled gripping presser member 60
 5 slidable in said rocker frame, an eccentric acting through a link for moving said member downwards to act upon the outside of the lip of the insole, a head movable pivotally on the rocker frame, a spring controlled 65
 10 gripping presser member slidable in said head, a rock lever fulcrummed on the rocker frame and provided with an adjustable screw adapted to engage the presser member in the movable head, a pin and slot connection 70
 15 between the head and the rock lever whereby movement of the latter independently of the head is permitted, a foot on said head adapted to contact with the lower end of a slot in the rocker frame to limit 75
 20 the movement of the head, and an eccentric acting through a link for imparting movement to the rock lever and the head so as to cause the presser member in the latter to move laterally and downwards to act 80
 25 upon the inside of the lip of the insole.
8. In an insole reenforcing machine, in combination, a rocker frame for imparting feed to the work and reenforcing strip, a spring controlled gripping presser member 85
 30 slidable in said rocker frame, an eccentric acting through a link for moving said member downwards to act upon the outside of the lip of the insole, a head movable pivotally on the rocker frame, a spring controlled 90
 35 gripping presser member slidable in said head, a rock lever fulcrummed on the rocker frame and provided with an adjustable screw adapted to engage the presser member in the movable head, a pin and slot connection 95
 40 between the head and the rock lever whereby movement of the latter independently of the head is permitted, a foot on said head adapted to contact with the lower end of a slot in the rocker frame to limit 100
 45 the movement of the head, and an eccentric acting through a link for imparting movement to the rock lever and the head so as to cause the presser member in the latter to move laterally and downwards to act upon the inside of the lip of the insole and a table on 105
 50 which the insole rests, said table having a screwed extension which is received in a tapped hole in the rocker frame so that by screwing the extension into or out of the hole the position of the table may be varied.

In testimony whereof I affix my signature.

JOHN VEASY COLLIER.
